JOHN F. KIRGAN, OF PHILLIPSBURG, NEW JERSEY, ASSIGNOR TO INGERSOLL-RAND COMPANY, OF JERSEY CITY, NEW JERSEY, A CORPORATION OF NEW JERSEY

BY-PASS CONDENSER

Application filed November 3, 1925. Serial No. 66,465.

This invention relates to surface condensers.

The capacity of a surface condenser depends upon the amount of cooling surface which is provided. The surface condenser usually comprises a shell within which are arranged a plurality of water conducting cooling tubes with which the steam is adapted to contact. The tubes are arranged generally parallel and at a distance from each other just sufficient to permit the steam to pass between at a relatively low velocity, for the reason that the friction loss of pressure increases substantially as the square of the velocity. Thus, if the tubes are spaced very closely more cooling surfaces would be provided but the friction loss of the steam passing through at the increased velocity in order to reach the tubes remote from the steam inlet would be extremely high and, although a high vacuum might be obtained at a point remote from the steam inlet, the friction loss would be so great that the difference in pressure between points at the steam inlet and the air outlet would be excessive. This would result in a relatively high absolute pressure on the steam inlet and to a large extent defeat the purpose of the condenser, which is, to maintain a high vacuum near the discharge of the steam consuming apparatus. To this end, hitherto the tubes have been spaced apart so as to permit steam to penetrate without great increase in velocity from the steam inlet portion of the condenser casing or shell to the tubes most remote from the inlet. A practical arrangement to accomplish this purpose has been to space the tubes closer together as the path of the steam approaches the most remote cooling tubes within the shell, which is to say that as the quantity of steam decreases by condensation the section of the path decreases correspondingly without loss of steam velocity. This results in a condition of uniform velocity within the condenser shell producing relatively high efficiency. A disadvantage of this arrangement, however, is that the wide spacing of the tubes near the steam inlet reduces the available cooling surface for a given sized condenser shell or casing enclosing the tubes.

It is an object of this invention to increase the amount of condensing surface within a given sized condenser shell and thereby to increase the steam condensing capacity without sacrificing the desired high vacuum at the steam inlet.

Other objects and advantages of the invention will be in part obvious and in part pointed out hereinafter.

The drawings illustrate a preferred embodiment of the invention and include,

Figure 1 which is a vertical cross-section through a condenser constructed in accordance with the practice of the invention, the section being taken along the line 1-1 of Figure 2 looking in the direction of the arrows, and

Figure 2 is a longitudinal horizontal section taken along the line 2-2 of Figure 1 looking in the direction of the arrows.

Referring to the drawings the surface condenser comprises a shell A having a steam inlet B and an outlet C for condensate. In this instance a devaporizer D is provided associated with the outlet C for cooling and devaporizing the uncondensable gases removed from the condenser by a vacuum pump (not shown). Within the shell A there are provided a plurality of tubes E arranged transverse to the path of steam flowing into the shell A through the steam inlet B and are preferably symmetrically arranged to form spaces of substantially equal area between adjacent tubes of a group. The tubes E are arranged in unbroken or solid groups of uniform depth throughout and extend to points closely adjacent the walls of the shell A. There are a plurality of groups, in this instance three and each group is in direct communication in the direction of steam flow with the adjacent groups. The group F is the uppermost group, and the group G lies intermediate the group F and the lower group H close to the outlet C. The tubes E are spaced more closely than would be common practise for steam from the inlet B intended to penetrate to the lowest group of tubes H through each of the other groups F and G. Steam is adapted to flow through the group F to the lowest row of tubes in

the group F. Steam to be condensed in the group of tubes G is preferably by-passed about the group F by means of by-pass passages formed by walls J parallel to the outer walls of the shell A, and a second pair of by-pass passages which is formed by the lower walls K adjacent the group of tubes G parallel to the outer walls of the shell A to by-pass steam directly from the inlet B to the lower group of tubes. Suitable tube supports L prevent the steam from passing longitudinally along the tubes E. The walls J and K prevent steam from entering the groups of tubes at the sides which would tend to retard the flow of steam from the top of the various groups.

In order to regulate the amount of steam by-passed about the various groups of tubes F and G means is provided including valves O located in the by-passes and preferably adjacent the upper rows of tubes of each group so that when open the valve will deflect the steam directly against the tube groups. The valves O are provided with suitable operating means such as rods P extending through stuffing boxes Q engaging the swinging valves O. The valves O are set to regulate the amount of steam by-passed which depends upon the atmospheric conditions and the temperature 30 of the cooling water in the tubes E.

In operation steam enters the steam inlet B of the shell A, some of the steam passing to the upper group F of tubes E to be condensed thereby, and the remainder of the steam being by-passed about the group F of the tubes E to the groups G and H and the amount of steam by-passed is regulated as above described by operating the valves O at the proper levels.

40 I claim:

1. A surface condenser comprising a shell having a steam inlet and an outlet for condensate and uncondensable gases, a plurality of groups of steam condensing tubes arranged transverse to the path of said steam flow, means to selectively by-pass steam about certain groups of tubes to another group of tubes including walls to prevent steam from entering the groups of tubes at the sides and means for controlling the amount of steam by-passed thereby.

2. A surface condenser having a shell, a steam inlet and an outlet for condensate and uncondensable gases, a plurality of groups of cooling tubes arranged transverse to the path of steam flow, by-passes about certain of said groups of tubes to conduct steam directly to another group of tubes adjacent the walls of said shell and having walls to prevent steam from entering the groups of tubes at the sides, and means for controlling the amount of steam by-passed thereby.

3. A surface condenser comprising a shell, 65 a steam inlet and an outlet for the conden-

sate and uncondensable fases, a plurality of groups of closely spaced tubes arranged transverse to the path of steam flow, and means to by-pass part of said steam from the steam inlet about certain of said groups of tubes to another group of tubes including walls to prevent steam from entering the groups of tubes at the sides.

4. A surface condenser comprising a shell having a steam inlet and outlet for condensate and uncondensable gases, a plurality of groups of cooling tubes arranged in superimposed relation transversely to the path of steam flow, said tubes being spaced from the wall of the condenser, and each group having walls at the sides of the same to prevent steam from entering the tubes at the sides, baffles hinged to the walls at the top of each group of tubes, said baffles being capable of swinging outwardly to divert steam through the walls onto the tubes or of swinging inwardly to by-pass steam around the groups.

5. A surface condenser comprising a shell having a steam inlet and an outlet for condensate and uncondensable gases, a plurality of groups of cooling tubes transverse to the path of steam flow normally adapted to conduct cooling water, and means normally adapted to by-pass steam about certain groups of tubes directly to another group of tubes including walls to prevent steam from entering the groups of tubes at the sides.

6. A surface condenser comprising a shell having a steam inlet and an outlet for condensate and uncondensable gases, a plurality of groups of cooling tubes transverse to the path of steam flow, means normally adapted to by-pass steam about certain groups of tubes, means to divert steam directly onto another group of tubes, and walls to prevent steam from entering the groups of tubes at the sides.

7. A surface condenser comprising a shell having a steam inlet and an outlet for condensate and uncondensable gases, a plurality of unbroken groups of cooling tubes arranged in successive layers and closely crowded together without steam lanes, the said groups being in direct communication in the direction of steam flow with adjacent groups, and means cooperating with the shell to form passages for by-passing steam about certain groups of tubes directly to another group of tubes.

8. A surface condenser comprising a shell having a steam inlet and outlet for condensate and uncondensable gases, a plurality of unbroken groups of cooling tubes arranged transversely to the path of steam flow, means cooperating with the shell to form passages for by-passing steam about certain groups of tubes, and a plurality of valves located at

spaced points along the passage for directing the by-passed steam directly onto each group of tubes.

9. A surface condenser comprising a shell having a steam inlet and outlet for condensate and uncondensable gases, a plurality of groups of cooling tubes arranged transversely to the path of steam flow, means to selectively by-pass steam about a group of tubes, and means to divert steam onto another of said groups of tubes, there being walls on the side of the tubes to prevent steam from entering the tubes at the sides.

10. A surface condenser comprising a shell having a steam inlet and outlet for condensate and uncondensable gases, a plurality of groups of cooling tubes arranged transversely to the path of steam flow, means to selectively by-pass steam about each group of tubes, and means to divert steam onto each group of tubes.

11. A surface condenser comprising a shell having a steam inlet and outlet for condensate and uncondensable gases, a plurality of groups of cooling tubes arranged transversely to the steam flow one above the other, means to selectively by-pass steam about the top group of tubes, means to divert the same onto the top group of tubes, means for selectively by-passing steam about the next lower group of tubes, and means for diverting the steam onto the next lower group of tubes.

12. A surface condenser comprising a shell having a steam inlet and outlet for condensate and uncondensable gases, a plurality of unbroken groups of cooling tubes arranged transversely to the path of steam flow, means cooperating with the shell to form a passage isolated from the groups for by-passing steam about certain of the groups of tubes, and separate means for directing the by-passed steam onto another group of tubes at the top thereof.

13. A surface condenser comprising a shell having a steam inlet and outlet for condensate and uncondensable gases, a plurality of groups of cooling tubes arranged transversely to the path of steam flow, means to bypass steam about certain groups of tubes, and separate means for directing the bypassed steam directly onto another group of tubes, there being walls at the sides of the tubes to prevent steam from entering the tubes at the sides.

14. A surface condenser comprising a shell having a steam inlet and an outlet for condensate and uncondensable gases, a plurality of unbroken groups of cooling tubes transverse to the path of steam flow, said groups terminating at points closely adjacent the walls of the shell and being of uniform depth throughout, means forming a passage in the shell adapted to by-pass steam about certain groups of tubes, and a plurality of valves

located at spaced points in the passage to deflect steam to each group of tubes.

In testimony whereof I have signed this specification.

JOHN F. KIRGAN.
